GARMENT HANGER

Rudolph Bernhardt, Chicago, Ill.

Application April 26, 1937, Serial No. 139,032

5 Claims. (Cl. 233—93)

This invention relates to hangers of the type used for supporting various garments and is particularly directed to a device of this kind having clamping means for holding the garments in position on the hanger. For this reason it is adapted for supporting gowns, light dresses, or like garments which are apt to slide off or become detached from the ordinary hanger. It may also be used for small articles such as stockings or the like which may be held in position by the clamping means.

The objects of this invention are to provide an improved garment hanger having means for holding the garments in position; to provide a clothes or garment hanger with adjustable clamping means for holding articles thereon; to provide a novel arrangement of applying clamping means to the hanger to reinforce and coat with the hanger parts; and to provide such advantages in construction and in use as will appear from the following description.

In the accompanying drawing illustrating this invention

Figure 1 is a front view showing the hanger with a garment supported thereon;

Figure 2 is an enlarged longitudinal sectional view through the central part of the hanger; and Figure 3 is a cross sectional view.

The particular form of hanger shown in this drawing comprises a garment supporting bar 5 which is preferably curved or formed in any desirable manner for such purpose and in the present instance is indicated as being formed of wood. The bar is supported by a hook or support 6 having a stem portion 7 which is driven or fits closely in a hole 8 in the center of the bar. This portion is also preferably provided with integrally formed ears or projections 9 which are forced into the wood and serve as keys for holding the bar in alignment with the hook.

My improved clamping arrangement includes a saddle or bracket 10 having a central longitudinal portion 11 which rests on the top of the bar and has a hole for receiving the stem 7. The lower surface of the plate or central portion 11 engages with the projections 9 to hold the hook firmly in position in the bar. The saddle 10 has side flanges 12 which extend over the sides of the bar, thus forming a channel for receiving the same. A pin or rivet 13 extends through the bar and flanges and serves to hold the parts in assembled position, this pin preferably passing through the bar just below the inner end of the stem 8 as shown in Figures 2 and 3. The saddle 10 has upwardly projecting arms 14 and 15

which are preferably flanged to stiffen the same. These arms have holes 16 and 17 adjacent to their upper ends which provide bearings for the clamping levers 18 and 19 which are pivotally and slidably mounted in such bearings. The outer ends of these levers are provided respectively with pads 20 and 21 of felt or the like for engagement with the garment. The inner ends of the clamping levers have holes 22 and 23 for engagement with the stem 7 so that they may move longitudinally of the same. The inner ends are urged upwardly or in clamping position by a spring 24 which is mounted on the stem 7 with its lower end abutting against the plate 11 and its upper end engaging with a U-shaped bearing member 25 which is slidably mounted on the stem and the ends of which engage with the respective levers 18 and 19. These levers are preferably curved in cross section to strengthen the same and the ends of the bearing member 25 are formed to fit in the curved portions of the levers as shown in Figure 3.

When a garment is to be hung on the hanger the inner ends of the levers 18 and 19 are pressed toward the bar to raise the outer ends upwardly as shown in dotted lines in Figure 1. This may be conveniently done by placing the thumb under the bar 5 and pressing downwardly on the inner ends of the levers with the first and second fingers straddling the stem 7. After the garment has been placed in position the clamping means is released and the clamping members 20 and 21 will hold the garment as shown at 26 securely on the bar.

While the illustration shows the clamping members in engagement with the shoulder portions of the garment it may also be noted in the case of formal dresses having shoulder straps or the like, the straps may be positioned inside of the clamping devices and these devices will engage with the bar, thus preventing the straps from sliding off from the bar.

While this indicates one use of the hanger, other uses will be readily apparent. It will also be noted that while I have shown a commercial or preferred form of this invention it may be modified, as for holding different garments and the construction may be varied without departing from the scope of the invention as set forth in the following claims, in which I claim:

1. A garment hanger comprising a wooden bar, a hook having a stem portion engaging with a hole in the bar and having projections adjacent to the top of the bar, a saddle fitting over the bar and engaging with said projections, means for

fastening the saddle to the bar, clamping levers pivotally and slidably mounted in the saddle and having their inner ends slidably secured to the stem, and yielding means coacting with the inner ends of the levers for pressing the outer ends toward the bar.

2. A garment hanger comprising a bar, a support having a stem engaging with the bar, said stem having projections thereon, a bracket fitting over the bar and engaging with said projections, means for securing the bracket to the bar, arms extending upwardly from said bracket, a pair of clamping levers having their fulcrums in said arms and their outer ends coacting with

10 the bar, the inner ends of said levers being slidably secured to the stem, and a spring coacting with the inner ends and the bar, tending to press said inner ends away from the bar.

3. In a clothes hanger, the combination of a 20 clothes supporting bar, a support secured to the center of the bar, clamping levers having their inner ends overlapping and each inner end provided with a slideable bearing engaging directly with the support and their outer ends coacting 25 with the bar for holding garments thereon, fulcrums carried by the bar which are slidably engaged by said levers, and yielding means coacting with the levers and tending to press the outer ends toward the bar, said inner ends of the 30 levers providing convenient finger pieces for swinging the levers to raise the outer ends.

4. In a clothes hanger, the combination with the usual bar and support therefor, of a saddle engaging with the bar, means for securing the saddle to the bar, arms extending upwardly from the saddle, levers fulcrumed in said arms, pads on the outer ends of said levers coacting with the bar for holding garments thereon, holes in the inner ends of said levers for receiving the support, a U-shaped bearing member slidably mounted on the support and having its ends 10 engaging with the respective levers, and a spring between said bearing member and the saddle, tending to press the bearing member away from the saddle.

5. A garment hanger comprising a bar, a hook 15 having a stem portion secured to the center of the bar, fulcrum members carried by the bar and spaced away from the stem, clamping levers pivotally and slidably mounted in said fulcrum members and having their inner ends slidably secured directly to the stem, and a spring coacting with the inner ends of the levers for pressing the outer ends toward the bar, the inner ends of the levers providing finger pieces whereby said 20 inner ends may be moved toward the bar to swing the outer ends away from the bar to permit placing of the garment thereon, substantially as described.

RUDOLPH BERNHARDT. 30
